UNITED STATES PATENT OFFICE.

WINFIELD S. JONES, OF BREA, AND HAROLD U. BAKER, OF LOS ANGELES, CALIFORNIA, ASSIGNEES OF THREE-EIGHTHS TO WINFIELD S. JONES, TWO-EIGHTHS TO HAROLD U. BAKER, AND THREE-EIGHTHS TO E. D. JONES, OF LOS ANGELES, CALIFORNIA.

PERFORATOR.

Application filed June 10, 1926. Serial No. 114,917.

This invention relates to perforators, and particularly to casing perforators. The invention belongs to that class of perforators wherein the perforating tool is adapted to be lowered within well casing or tubing, and when the perforator has reached the desired zone within said casing to perforate the casing.

The invention has for an object the provision of a perforator which is easily lowered within well tubing or casing, and which may be easily removed from the well tubing or casing after the same has been perforated.

A further object is the provision of a perforator which is inexpensive of construction, simple to operate, fool-proof, with practically no working parts to get out of order.

A further object is the provision of a perforator wherein the perforator is directly secured to the casing against movement during operation of said perforator.

In practicing the invention the perforator is provided with a curved cutting blade, a body formed to receive said cutting blade, slip members carried by the body, and a friction member, there being a frangible member between the friction member and a sleeve associated with the body. The sleeve in turn is secured to the slip, whereby when the frangible member is broken the slip may be brought into engagement with casing to hold the body in a definite position within the casing, and whereby movement of the blade will perforate the casing.

Another object is the provision of a perforator wherein the perforating member is so formed and constructed as to allow its ready withdrawal from tubing or casing after the blade has penetrated such tubing or casing.

A further object is the provision of a perforator adapted to easily perforate concentric strings of tubing or casing without a binding of the perforating member.

With the above and other objects in view, the invention consists in the novel and useful provision, formation, construction, association and relative arrangement of parts, members and features, all as shown in certain embodiments in the accompanying drawings, described generally and more particularly pointed out in the claims.

In the drawings:

Figure 1 is an elevation of the improved perforator;

Figure 2 is a vertical sectional view of the improved perforator within well casing;

Figure 3 is a further sectional view of the perforator within well casing and showing separation of certain parts thereof;

Figures 4 and 5 are vertical sectional views showing the effect of movement of certain parts of the perforator;

Figure 6 is a vertical sectional view of the perforator and showing the blade element thereof perforating concentric strings of casing; and,

Figure 7 is a cross sectional view of a modified form of the perforator showing two slip members carried by the body.

Corresponding parts in all the figures are designated by the same reference characters.

Referring with particularity to the drawings the improved perforator is designated as an entirety by A, and the same includes a body a, a member b movable relative to the body, gripping means c and d, a cutter e, and means f for actuating the cutter, all of which elements are used in practicing one embodiment of the present invention. The body a is formed at one end with a circular chamber or bore 1, and likewise provided with screw threads 2. Adapted to be received in part within said bore 1 is a plunger 3 constituting a part of the actuating means f for the cutter e. This plunger is formed with a head 4 and a stem or arm 5, the stem or arm 5 being substantially circular, and passed through a guide nut 6, which nut is screw-threaded to the threads 2. The cutter e is arcuate or curved and adapted to be fitted within a curved bore 7 which communicates with the bore 1 and externally of the body a, as shown at 8. The cutter blade is secured to the plunger by means of a link 9, which link is pivoted respectively to the plunger head 4 and an end of the cutter blade as indicated at 10 and 11. The cutter blade is formed with a substantially sharp or pointed object engaging nose 12. Thus if the plunger were allowed movement the cutter blade would reciprocate within the curved bore 7 outwardly of the body and inwardly thereof. The cutter body is reduced as to diameter at the end

opposite the chambered end 1, as shown at 13, and the member *b* which constitutes in reality a sleeve is movable upon such reduced end. The said sleeve is provided with a base portion 14 having a central bore 15. The body *a* at the reduced end portion is recessed at 16 to in part confine a latch 17 pivoted to said body at 18 and the said latch has a notched end 19. The sleeve *b* is slotted at 20 so that the said latch may when in one position, as shown in Figure 2, engage an end wall 21 bounding said slot 20. The body *a* is formed to carry one or more of the slips *d*, and the body to this end is formed with a plane surface 22 which is at an angle to the outer surface of the body. This construction forms a ledge 23. A bore 24 is passed through the body at the ledge portion 23 and adjacent the portion of reduced diameter of said body. The slip *d* is substantially wedge-shaped and is adapted to be substantially flush with the outer surface of the body when the same is fitted against the inclined wall 22, as shown in the figures. To retain the slip to the body the body is formed with a dove-tail slot or race 25 and the slip is correspondingly dove-tailed so as to fit within such race. An arm 26 is passed through said bore 24, and connected to the slip *d*. The opposite end of said arm is secured to the sleeve *b*, as by providing said arm with an angular extremity 27 received in a transverse bore 28 of the sleeve. Adapted to be fitted within the sleeve *b* and likewise slidable therein, is a head 29, and joined with said head is a mandrel 30 the shank portion of which is passed through the bore 15 in a base of the sleeve. Carried on this mandrel and slidable thereon is the friction spring member *c* which includes two spring arms 31 and 32 which are secured to top and bottom collars 33 and 34, which collars are carried on the mandrel. The said member *c* is prevented from escape from the mandrel in any suitable manner such as by a nut 35 screw-threaded upon an end of the mandrel. To maintain the various parts in association, as shown in Figure 2, a frangible pin 36 is passed through the stem 3, and which pin will bear against the top surface of the nut secured to the body, and thus hold the plunger elevated and maintain the cutter within the bore 7 of the body. Likewise a frangible pin 37 is passed through aligned bores in the sleeve *b* and the head 29, whereby the mandrel is maintained in a certain position relative to said sleeve. The position is likewise such that the latch 17 is held so that the notch 19 bears against the head 29, as shown at 38. The latch is kept in tight engagement with the head and likewise the sleeve through the medium of a leaf spring 39 secured to the reduced portion of the body and bearing against the top edge of the said latch, as shown at 40.

65 The operation of the device is as follows:

If we assume that the frangible member 36 is maintaining the plunger 3, which constitutes a portion of the means *f*, in such a position that the plunger head is bearing against the nut secured to the body *a*, the cutter *e* 70 will be within the bore 7 and not exposed outwardly of such bore. Furthermore, if the frangible member 37 is unbroken, the sleeve *b* and the head 29 will be maintained in such relation that the latch 17 bears against such head, as shown at 19, and likewise the part 21 of the sleeve. When the parts are so positioned the slip member *d* will have its outer face conforming to the general curvature of the body. Likewise it will be seen that the 80 mandrel 30 has its end portion extending below the collar 34. The parts just described will be in the position shown in Figure 2. If now the tool is secured through the connection 41 to tubing running to the surface 85 of the well, the perforator as an entirety may be lowered to any desired zone within well casing. If, as the drawings indicate, it is desired to perforate two concentric strings of casing, and having reached the desired zone 90 for such perforations, further downward movement of the perforator is stopped and upon giving the perforator a sudden upward pull the frangible member 37 will be sheared, as shown at 42, due to the fact that the member *c* will grip the inner surface of the casing, and the collar 34 with the nut 35 carried by the mandrel, and likewise further due to inertia effect, the member *c* tending to remain stationary while other parts of the perforator 95 are moved. The parts of the perforator will now assume the position indicated in Figure 3 wherein the latch 17 will become disengaged from the part 21 of the sleeve, and likewise an edge of the head 29. 105

The upward movement of the perforator body is continued until the head 29 reaches the lowermost position that it may assume within the sleeve, as indicated in Figure 4. Upon reversing the movement, that is, moving the body of the perforator downwardly, the slip, due to its connection with the sleeve will now move along the inclined face of the body and the teeth of the same, as shown at 43, will bite into the inner surface of the 115 inner string of casing. Upon sudden downward movement to create an impacting force, the pin 36 will be sheared as shown in Figure 6, and the cutter will pierce the casings as shown at 44 and 45 to perforate the same. Removal of the cutter is an easy matter, as the inclined cut given the casings and the inclined relation of the cutter to said casings 120 renders it only necessary to exert an upward pull upon the plunger 3 to pull the cutter 125 from such perforations. Thus sticking of the cutter within the casings is entirely done away with, a feature of great importance, where more than one casing is to be perforated at a time. The perforator is easily 130

- withdrawn from the well hole and as many places as desired may be perforated in the manner indicated. The slip at all times carries the weight of the body and likewise prevents downward movement of the body while the cutter is operating. As indicated in Figure 7, more than one slip may be provided, the slips being angularly related as shown in the figure.
- 10 It is obvious that various changes and modifications may be made in practicing the invention, in departure from the particular showing, without departing from the true spirit of the invention.
- 15 Having thus disclosed our invention, we claim and desire to secure by Letters Patent:
1. Improvements in perforators, including a cutter, a body formed to receive said cutter, friction means, a sleeve carried by said body and connected with said friction means, and a slip movable relative to the body and associated with the sleeve, and a frangible member between the friction means and the sleeve and adapted when sheared to release the slip from a given position.
  2. Improvements in perforators adapted to be placed within well casing, including a body formed with a chambered portion, a plunger within said chambered portion, a cutter blade secured to said plunger, a sleeve carried on the body, a friction member, and frangible means between the friction member and the sleeve, and means between the body and sleeve for maintaining said frangible member intact during movement of the perforator within the casing.
  3. Improvements in perforators adapted to be placed within well casing, including a body, a sleeve carried at one end of said body, a head within said sleeve and a frangible member between the head and the sleeve, a mandrel carried by the head, and a friction member upon said mandrel.
  4. Improvements in perforators adapted to be placed within well casing, including a body, a sleeve carried at one end of said body, a head within said sleeve and a frangible member between the head and the sleeve, a mandrel carried by the head, and a friction member upon said mandrel, a slip carried by the body and linked to the sleeve, and whereby downward movement of the body will move the slip into engagement with the casing to stop such downward movement of the body.
  5. Improvements in perforators adapted to be placed within well casing, including a body, a sleeve carried at one end of said body, a head within said sleeve and a frangible member between the head and the sleeve, a mandrel carried by the head, and a friction member upon said mandrel, a slip carried by the body and linked to the sleeve, and whereby downward movement of the body will move the slip into engagement with the casing to stop such downward movement of the body; in combination with a cutter adapted to be moved from the said body when the slip is engaging the casing.
- In testimony whereof, we have signed our names to this specification.

WINFIELD S. JONES.
HAROLD U. BAKER.
